US0D1030302S

(12) **United States Design Patent** (10) **Patent No.:** **US D1,030,302 S**
(45) **Date of Patent:** **** Jun. 11, 2024**

(54) **BACKPACK**

(71) Applicant: **GUANGZHOU HAOKUN E-COMMERCE CO., LTD.**,
Guangzhou (CN)

(72) Inventor: **Zhou Peng**, Shaoyang (CN)

(73) Assignee: **GUANGZHOU HAOKUN E-COMMERCE CO., LTD.**,
Guangzhou (CN)

(**) Term: **15 Years**

(21) Appl. No.: **29/850,891**

(22) Filed: **Aug. 24, 2022**

(51) LOC (14) Cl. **03-01**

(52) U.S. Cl.

USPC **D3/216**; D3/217

(58) **Field of Classification Search**

USPC D3/216, 217, 226, 229–233, 240–246,
D3/303, 318, 321–328; D9/703–707, 710

CPC A45F 3/02; A45F 3/04; A45C 3/06; A45C
15/00
